VARIABLE CAPACITY VANE PUMP

Thomas J. Thatcher, Huntington Station, N. Y.

Application February 19, 1946, Serial No. 648,676

3 Claims. (Cl. 103—120)

1

This invention relates to fluid transmissions, and more particularly to an apparatus for the pumping and circulation of fluid.

A primary object of this invention is the provision of an improved apparatus for the circulation of fluid for any desired purpose, such as a pump, or for motive power, or for other usages.

An additional object of the invention is the provision of such a device having means whereby the quantity, and hence the effective pressure of the fluid circulated may be readily varied as desired.

A still further object of the invention is the provision of such a device characterized by a pair of arcuate, substantially semi-circular shoes constituting an interior housing, surrounding a rotor, and provided with means whereby the spacing of such shoes from the rotor may be readily varied to effect an adjustable flow of fluid as desired.

Still a further object of the invention is the provision of such a device, whereby upon appropriate adjustment of the shoes constituting said interior housing, the device may be rendered inoperative, or neutral.

Still other objects reside in the provision of such a device which is sturdy and durable in construction, reliable and efficient in operation, and relatively simple and inexpensive to manufacture and assemble.

Further objects reside in the combinations of elements, arrangements of parts, and features of construction, all as will be more fully pointed out hereinafter and disclosed in the accompanying drawing, wherein there is shown a preferred embodiment of this inventive concept.

In the drawing:

Figure 1 is a side view, partially in elevation and partially in section, certain portions thereof being broken away, disclosing one embodiment of this inventive concept.

Figure 2 is a sectional view, taken substantially along the center line of Figure 1, certain portions thereof being broken away to show certain interior mechanism.

Figure 3 is a reduced partially schematic sectional view disclosing the operative relation of certain parts of the mechanism showing the pump parts in position for maximum pumping capacity;

Figure 4 is a sectional view taken substantially along the line 4—4 of Figure 1, as viewed in the direction indicated by the arrows;

Figure 5 is a cross-section taken substantially on the line 5—5 of Figure 2 and substantially

2

perpendicular to the axis of pump rotation, showing the pump parts in neutral or non-pumping condition;

Figure 6 is a cross-section similar to Figure 5 showing the parts in position for maximum pumping capacity; and

Figure 7 is a view similar to Figure 3 but showing the parts in neutral or closed position as in Figure 5.

Similar reference characters refer to similar parts throughout the several views of the drawing.

Having reference now to the drawings, the device of the instant invention is comprised of an outer casing generally indicated at 10, and of substantially cylindrical shape, which may include a receptacle portion 11 closed, as by a base plate 12 secured in position, as by a plurality of screws 13. The receptacle 10 is provided with centrally positioned external bosses 14 on opposite sides thereof, within which are positioned packing rings 15 held in position, as by packing nuts 16, the latter being centrally apertured to accommodate a drive shaft 17. Bearings 18 are also provided for the purpose of journaling the rotation of the shaft 17, which, it may be here pointed out, is adapted to be rotated by any suitable source of power.

The shaft 17 has suitably affixed thereto for rotation therewith a rotor 20 cut away, as at 21, on its opposite faces, and provided with channels or grooves 22 to accommodate sealing rings 23, the purpose of which will be more fully pointed out hereinafter.

Suitable recesses peripherally positioned at spaced points about the rotor 20 accommodate vanes 25 pivotally secured, as by pivots 26 and spring biased outwardly, as by springs 27 seated in recesses 28. In the illustrative embodiment shown three of the vanes 25 are disclosed, but it will be readily understood that any desired number may be provided in accordance with the use to which the mechanism is to be put.

Positioned peripherally about the rotor 20 and within the outer housing 10 is an inner housing comprising two pivotally-mounted substantially semi-circular shoes, generally indicated at 30 provided with semi-circular central apertures 31, and adapted, when moved into juxtaposition with the rotor, as illustrated in Figure 5 and more fully described hereinafter, to closely surround the same. Each of the shoes 30 is of channel-shaped cross-section, and includes spaced apart, radial side flanges 32 provided with grooves 33, which accommodate the outer portions of the

sealing rings 23, thus effecting a relatively fluid-tight seal between the rotor and the inner housing shoes 30.

Fluid inlet means are provided in the housing 10 and take the form of extending bosses 35 provided with ball check valves 36 spring pressed, as by springs 37, and provided with bores 38 seating the valves 36 in communication with passageways 39 which extend to inlet ports 40 in communication with the interior of the inner housing shoes 30.

The passageways 39 extend through interiorly positioned projecting portions 41 of the housing 10, which portions together with flanges 32 positioned on each of the shoes 30 form a dove-tail joint for the alignment of the shoes 30 and their pivotal movement in a manner to be more fully described hereinafter. Outlet pipes 45 extending through the projections 41 and shoes 30 serve as pivots for pivotally mounting the shoes 30 in the housing. Each outlet pipe 45 is provided with a centrally positioned aperture 46 in communication with the interior of the housing 30, and from which a passageway 47 extends to a ball valve 48 spring pressed, as by a spring 49, and seated in a boss 50 exteriorly of the housing 10.

The ends of the pipes 45 opposite the bosses 50 are suitably seated in interiorly positioned bosses 51 and drainage plugs 52 are provided at the outer ends of the outlet 45.

Referring now particularly to Figures 3, 5, 6 and 7, it will be seen that each of the shoes 30 is pivoted at one extremity to the housing by a respective outlet pipe 45, and that separation of the shoes, in a manner to be more fully hereinafter described, will space certain points of their centrally positioned concavities at a greater distance from the periphery of rotor 20 than others (see Figures 5 and 6). It will also be seen that the points spaced most closely to the rotor 20 will be directly adjacent the outlet and a space 55 is provided adjacent each outlet passage 47 to permit the forcing of fluid therethrough by the vanes 25 as the rotor is rotated by the shaft 17. Thus, it will be seen that when the shoes 30 are positioned in close relation to the rotor 20, the vanes 25 will be held in their associated recesses and substantially no circulation of fluid permitted. A very small amount of fluid for lubricating and cooling purposes may be permitted even when the shoes are in the closed or neutral position shown in Figure 5. As the shoes are moved outwardly to the position shown in Figure 6, for example, fluid will be admitted through the inlet port and swept by the vanes through a substantially semi-circular path to the outlet, centrifugal force and the pressure of the springs 27 serving to hold the vanes closely against the inner surfaces of the shoes.

Means are provided for adjusting the shoes 30 in the manner described and take the form of links 56, each pivotally secured at one end, as on a pivot pin 57, to one of the shoes 30 at a point substantially diametrically opposite the pivot point comprised of the outlet pipe 45. The opposite end of each link 56 is secured, as by a pivot 58, to a circular member 59 provided with gear teeth 60. The gear teeth 60 mesh with the teeth 61 of a cog gear 62 mounted on a shaft 63 which extends through a suitable boss 64 in the outer housing 10 and terminates in an adjusting knob 65.

It will thus be seen that rotation of the knob 65 through the gear teeth 61 and 60 serves to rotate the member 59 and thus through the links 75

56 vary the relative position of the shoes 30 with respect to the central member 59 and correspondingly vary the spacing thereof with respect to the rotor 20.

5 It will be readily apparent that as the spacing of the shoes 30 is varied, the quantity of fluid forced through the pump by the vanes 25 will also be varied, and accordingly the pressure exerted by the device.

10 It is to be noted that the check valves in the inlet and outlet means for the device serve to preclude the circulation of fluid until such time as sufficient pressure is built up in the apparatus to freely circulate the fluid as desired.

15 From the foregoing it will now be seen that there is herein provided an improved fluid circulating device which accomplishes all the objects of this invention, and others, including many advantages of great practical utility and commercial importance.

20 As various embodiments may be made of this inventive concept, and as various modifications may be made in the embodiment hereinbefore shown and described, it is to be understood that all matter herein is to be interpreted merely as illustrative and not in a limiting sense.

I claim:

1. A fluid pump comprising a housing providing an annular receptacle, a shaft journaled in said housing, a rotor on said shaft within said housing receptacle, said rotor having angularly spaced recesses in the outer portion thereof, vanes carried by said rotor and pivotally mounted, one in each of said recesses, a pair of interiorly-concave, arcuate shoes in said housing receiving the outer portion of said rotor, a pair of fluid outlet pipes disposed at opposite sides of said rotor, each pivotally connecting an end of a respective arcuate shoe to said housing, means operatively connected with said shoes and operated from outside said housing for moving said shoes toward and away from said rotor, means providing fluid inlet and outlet passages for the spaces between said shoes and said rotor, and means providing a seal between each side of said rotor and said shoes.

2. A fluid pump comprising a housing providing an annular receptacle, a shaft journaled in said housing, a rotor on said shaft having angularly spaced recesses therein, vanes carried by said rotor pivotally mounted, one in each of said recesses, a pair of interiorly-concave, arcuate shoes in said housing receiving the outer portion of said rotor, means pivotally securing one end of each of said shoes to said housing for movement of said shoes toward and away from said rotor, a gear wheel rotatably mounted in said housing adjacent said shoes, means operatively connecting said gear wheel with said shoes for movement of said shoes toward and away from said rotor upon rotation of said gear wheel, gear means meshing with said gear wheel and rotated from outside said housing to rotate said gear wheel, means providing fluid inlet and outlet passages for the spaces between said shoes and said rotor, and means providing a seal between each side of said rotor and said shoes.

3. A fluid pump comprising a housing providing an annular receptacle, a shaft journaled in said housing, a rotor on said shaft within said housing receptacle, said rotor having angularly spaced recesses in the outer portion thereof, vanes carried by said rotor and pivotally mounted, one in each of said recesses, a pair of interiorly-concave arcuate shoes in said housing receiving the outer portion of said rotor, means

pivotaly securing one end of each of said shoes to said housing for movement of said shoes toward and away from said rotor, means operatively connected with said shoes and operated from outside said housing for moving said shoes toward and away from said rotor, means providing fluid inlet and outlet passages for the spaces between said shoes and said rotor, said rotor and said shoes having complementary annular grooves in the opposite side portions thereof, and a pair of sealing rings seated in said grooves and disposed one at each side of said rotor to provide fluid seals between said rotor and said movable shoes.
